UNITED STATES PATENT OFFICE.

THOMAS M. CONDON, OF VALLEY CITY, NORTH DAKOTA.

FAN.

1,324,231.

Specification of Letters Patent.

Patented Dec. 9, 1919.

Application filed July 14, 1919. Serial No. 310,574.

To all whom it may concern:

Be it known that I, THOMAS M. CONDON, a citizen of the United States, residing at Valley City, in the county of Barnes and State of North Dakota, have invented certain new and useful Improvements in Fans, of which the following is a specification, reference being had to the accompanying drawings.

10 This invention relates to an improved fan, particularly of the electrically operated type, and an object of the invention is to provide a fan of this kind, which, when in motion will throw a blast of air covering a radius of from one hundred to one hundred and sixty degree angle, instead of throwing a straight current of air substantially directly in front of the fan, as is accomplished by the ordinary fan, thus eliminating the necessity of mounting the fan to revolve on an arcuate curve.

20 A further object of the invention is to provide a fan of this kind having blades curved outwardly and rearwardly, the end portions of the blades being of greater curves than the bodies of the blades, thereby eliminating the straight blades, so as to discharge or throw a current of air of a wide area. While it has been found that a current of air from a fan of this kind may not be as strong as emanating from the ordinary straight bladed fans, it will be a steady current, covering considerable area.

30 35 A further object of the invention is to provide a fan wheel having curved blades of the kind heretofore mentioned, and means for pivotally mounting the blades in coöperative connection with the revolving shaft 40 of the fan motor, in combination with means carried by the shaft, coöperating with the connecting ends of the blades for adjusting the blades, so as to regulate the positions 45 of the blades, thereby governing the area of the current of air, as well as regulating the angle of the current of air.

40 A further object of the invention is the provision of means for changing the disposition of the blades, that is changing all the 50 blades correspondingly or changing the blades at different angles, whereby the current of air may be altered as may be found necessary.

55 While the design and construction at present illustrated and set forth is deemed preferable, it is obvious that as a result of

a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and claimed.

In the drawings:

Figure 1 is a plan view of an electrically operated fan constructed in accordance with the invention, showing the blades curved, and the means for adjusting the blades at different angles, as shown in dotted lines and in full lines.

Fig. 2 is a sectional plan view, thereby showing the detail construction of the adjusting means, showing the blades adjusted at angles different to those shown in full and dotted lines in Fig. 1.

Fig. 3 is a front view of Fig. 1.

Fig. 4 is a sectional plan view of a modified construction of the adjusting means for the blades, in which case only two blades are used.

Fig. 5 is a plan view of an electrically operated fan, showing the adjusting means for the blades eliminated.

Referring more especially to the drawings, 1 designates a conventional form of electric motor, adapted for use in connection with electric fans, for operating the fan wheels. 90 This motor is provided with the usual braid covered conductors, in the form of a cord, as shown at 2, and provided with a plug 3, to engage a socket (not shown), whereby electrical energy may be supplied to the motor. 95 The shaft 4 of the motor at its outer end portion is provided with a threaded bore 5. The end of the shaft has a rectangular reduced part 6, to receive the washer or plate 7, adjacent which a second plate 8 is arranged, the same also engaging the rectangular reduced part 6. This plate 8 is provided with radial arms 9 having spaced forks 10 at the outer ends, between which upon the pins 11 the fan blades 12 are mounted. In fact, the blades are provided with slots 27, through which the pins 11 extend. These blades have their inner adjacent ends fastened at 28 to the hub 29, through which the screw 30 extends. A 111. nut 31 is threaded upon the screw 30, so as to coöperate with the head of the screw, to

hold the hub in different adjusted positions. By loosening the nut 31 and adjusting the screw axially through the shaft 4, the blades may be adjusted in different angles. For 5 instance, when the head is moved axially in a direction with the shaft 4, the blades will move slightly radially, in which case the current of air emanating from the blades will be thrown in a smaller area than when 10 the blades are adjusted, by moving the screw axially from the shaft 4. After the hub 28 has been adjusted in a position to hold the blades in the desired position, the nut 31 may be tightened. By adjusting the screw 15 axially from the shaft 4, the outer ends of the blade will be moved farther rearward, and in this case the area of the current of air will be increased. The fan blades 12 are curved outwardly and rearwardly as shown, 20 the outer portions of the blades being curved greater than the body portions, so that when the blades are in motion, they will throw a current of air of a wide range, that is of a wide area, more so than the ordinary fixed 25 fan wheel.

Beyond the rectangular part 6 a cylindrical reduced extension 13 is formed, which is engaged by a dished washer plate 14, there being a nut 15 threaded upon the extension 30 13, thereby holding the plates 7, 8 and 14 securely clamped together.

As shown in Fig. 4, a screw 16 threads into the bore 5, and is provided with a head 17. This screw passes through the slots 18 of the 35 inner adjacent overlapping ends of the short arms of the fan blades. Interposed between the adjacent overlapping ends is a pair of nuts 19 and 20. The nut 19 coöperates with the head 17 of the screw, for clamping the 40 inner end of certain of the blades, say for instance one of the blades, while the nut 20 coöperates with an additional nut 21, for holding the inner arm of a certain other blade in a different position to the position of the 45 other blade. By this construction, it will be seen that the blades may be arranged at various angles relative to each other. However, if desired, the blades may be adjusted at cor-

responding angles relative to each other, by 50 loosening upon the various nuts, and rotating the screw inwardly through the bore of the shaft, after which the nut may be tightened, to hold the blades in position. By adjusting the angles of the blades, and owing 55 to the blades being curved as shown, the blades will throw a current of air of a wide area.

In Fig. 5, the means for adjusting the blades is eliminated, and instead the blades are mounted upon a hub 22, which is mounted on the rectangular part 23, there being opposing plates 24, to hold the hub 22 in position and a nut 25 is threaded upon the reduced cylindrical and threaded extension 26, to hold the parts in place. In this construction of device, the blades are curved, as in the previous instance, the ends of the blades being curved greater than the bodies of the blades, so as to throw a current of air 70 a wide area.

It is to be understood that this particular construction of fan blade and means for adjusting the blade, may be applied to any form of electric fan, even those that are suspended from the ceiling and are operated by 75 slow motors, so that the blast of air when descending will spread considerably.

The invention having been set forth, what is claimed as new and useful is:

In a device as set forth, the combination 80 with a motor driven shaft, of a blade holder carried by the shaft, fan blades having slot and pin connections with the outer portions of the holder, the inner adjacent ends of the blades having a hub and a member passing 85 through the hub and being adjustable axially relatively to the shaft and connected thereto, whereby the blades may be adjusted at different angles.

In testimony whereof I hereunto affix my 90 signature in the presence of two witnesses.

THOMAS M. CONDON.

Witnesses:

M. J. ENGHART,
JOSEPHINE EFTELAND.
